UNITED STATES PATENT OFFICE.

RICHARD FLEMING, OF LYNN, MASSACHUSETTS, ASSIGNOR TO GENERAL ELECTRIC COMPANY, A CORPORATION OF NEW YORK.

RESISTANCE UNIT.

No. 845,225.

Specification of Letters Patent.

Patented Feb. 26, 1907.

Application filed January 26, 1906. Serial No. 298,003.

To all whom it may concern:

Be it known that I, RICHARD FLEMING, a citizen of the United States, residing at Lynn, county of Essex, State of Massachusetts, have invented certain new and useful Improvements in Resistance Units, of which the following is a specification.

This invention relates to improvements in resistance devices for electric circuits, and has for its object the provision of a device of this character which will have a broad application in connection with electric circuits wherever it is desired to provide a cheap, safe, and efficient insulation which will stand a high temperature, in addition to sudden changes of temperature, while at the same time retaining its insulating properties.

In the art to which this invention relates it has been common to embed the conductor in heat-refractory insulating materials—such as clay, cement, &c.—and likewise to attach the conductor to a base, which may be either of conducting or insulating material, by means of some heat-refractory insulating material, such as enamel, the conductor being applied to the enamel while the latter is in a plastic condition, the whole being afterward baked at a high temperature. Devices of this character are open to many objections. In the first place, the fusing-point of the enamel is exceedingly high, and to embed the conductor in this enamel, and thus raise it to so high a temperature, is oftentimes very injurious. Moreover, the changes in temperature and the expansion and contraction of the conductor caused thereby crack the enamel. Furthermore, when the conductor is embedded in the enamel it is difficult to repair an injury either to the conductor or to the insulation itself.

In carrying out my invention it is my object to provide a resistance device which may be used either where heat is the object desired, as in the case of electric heaters, or where heating is only incidental, as in the case of rheostats. I likewise use the enamel base; but instead of embedding the conductor in the enamel I provide supporting or attaching means which is heat-refractory and an insulator which I embed in the enamel and then attach the conductor to the supporting device. I find that a very convenient arrangement is to take a resistance fab-

ric which is composed of insulating elements having a resistance-conductor running back and forth therethrough and attach the insulating element to the enamel. This insulating element may be flexible—as, for instance, asbestos cords having a conductor woven back and forth through the cords—or it may be a web of material composed of insulating-buttons, with a conductor binding them together. In either case the conductor not being embedded is free to expand and contract independently of the enamel. My invention therefore comprises a resistance device in which this conductor is enameled to a base through the medium of a supporting or attaching means, the conductor itself not being attached to the enamel.

I do not, of course, limit my invention to the use of enamel; but any material of this character which will stand the temperature to which it will be subjected will come within the scope of my invention, and it is not, moreover, essential that the material be an insulator, so long as the attaching means serves to insulate the conductor from the base.

In the drawings, Figure 1 is a plan view of a resistance device embodying my invention. Fig. 2 is a partial transverse section thereof somewhat enlarged. Fig. 3 is a plan view of another form of my invention, and Fig. 4 is an elevation of the same.

Referring to the drawings, Figs. 1 and 2, 10 is a supporting-base and may be of any desired material—such, for instance, as cast-iron—or it may be of insulating material, such as slate, soapstone, or porcelain. 90 Mounted upon this base is a flexible resistance fabric composed of cords 11, of some heat-resisting material, such as asbestos. A resistance-conductor 12 traverses back and forth alternately over and under the cords, 95 forming the woof of the fabric. If desired, woof-threads 13, of asbestos, may also be supplied, as shown in patent to Heath, No. 557,386. This fabric is attached to the base 10 by means of a material 14, in which the cords 11 are embedded. This material may be commercial enamel or any material which will stand a high temperature and which will securely fasten the cords thereto, it also being essential that the material shall assume a 100 soft or plastic condition and will harden un-

der heat. The conductor 12 is not embedded in the enamel, and although it is securely fixed thereby it is still free to respond to changes in temperature independently of the 5 enamel. The cords 11 form a yielding support for the conductor and at the same time are strong and will stand without danger a temperature equal to the fusing-point of the enamel.

10 In Figs. 3 and 4 I have shown another form in which the means for supporting the conductor consists not of yielding elements, but of rigid insulating-buttons 15. These buttons and the conductor running therethrough 15 form a fabric such as is described in the application of Harry E. Heath, Serial No. 236,457, filed December 12, 1904. These buttons are preferably made with slots 16, so that in case one is destroyed it can be easily 20 replaced. These buttons are likewise embedded in the enamel, as shown, while the conductor is entirely free of the enamel. The buttons and conductor may be applied to the base in the form of a fabric, or the buttons 25 may be enameled to the base and the wire then threaded back and forth through the buttons.

Various modifications and changes will suggest themselves to those skilled in the art 30 which will be within the spirit of my invention, and it should be understood that I do not limit my invention to the precise arrangement of elements nor to the material used except in so far as it is limited by the scope of 35 the claims annexed to and forming a part of this application.

What I claim as new, and desire to secure by Letters Patent of the United States, is—

1. The combination with a base, of a flexible 40 resistance fabric enameled thereto, the resisting element being unembedded whereby it is free to move independently of the enamel.

2. A resistance unit comprising an enameled 45 base, insulating supporting means embedded therein, and a resistance-conductor

running back and forth through said support above the surface of the enamel.

3. A resistance unit comprising an enameled base, a resistance-conductor running 50 back and forth above the surface of the same, and means embedded in said enamel for supporting said conductor.

4. A resistance unit comprising a base, conductor-attaching devices enameled there- 55 to, and a resistance-conductor running back and forth above the surface of the enamel in engagement with the attaching devices.

5. A resistance device comprising a base, a coating of vitreous material thereon, a re- 60 sistance-conductor running back and forth above the surface thereof, and insulating supporting means embedded in said material for supporting said conductor.

6. A resistance device comprising a base, a 65 resistance-conductor running back and forth across the same, supporting means for said conductor, and a vitreous enamel embedding the supporting means and leaving the conductor unembedded whereby it is free to 70 move independently of the base.

7. A resistance device comprising a base having a coating of refractory material there- 75 on, a series of heat-resistant insulating attaching devices embedded therein, and a re- sistance-conductor running back and forth above the surface of the material in engage- ment with the attaching devices.

8. A resistance unit comprising a base having a coating of enamel thereon, a series 80 of heat-refractory insulating attaching de- vices embedded therein, and a resistance- conductor running back and forth above the surface of the enamel and engaging the successive devices on their opposite sides. 85

In witness whereof I have hereunto set my hand this 25th day of January, 1906.

RICHARD FLEMING.
